DESIGN FOR A CHILD'S DISH

Marion Weeber, New York, N. Y., assignor to National Silver Company, New York, N. Y., a corporation of New York

Application April 17, 1948, Serial No. 145,798

Term of patent 14 years

(Cl. D44—15)

To all whom it may concern:

Be it known that I, Marion Weeber, a citizen of the United States, residing in the city, county, and State of New York, have invented a new, original, and ornamental Design for a Child's Dish, of which the following is a specification, reference being had to the accompanying drawing, forming a part hereof, in which:

Fig. 1 is a plan view of a child's dish embodying my new design;

Fig. 2 is a vertical section taken on line 2—2 of Fig. 1;

Fig. 3 is a vertical section taken on line 3—3 of Fig. 1.

The bottom of the child's dish is of conventional contour.

I claim:

The ornamental design for a child's dish, as shown and described.

MARION WEEBER.
